VAPOR CONDENSER AND LIQUID RADIATOR

Nathan C. Price, Hollywood, Calif.

Application November 20, 1940, Serial No. 366,374

8 Claims. (Cl. 60—96)

This invention relates to improvements in vapor condensers and/or liquid radiators, and more particularly to a novel construction and arrangement for such apparatus, wherein air at atmospheric temperature is utilized as the means for absorbing and dissipating the heat. Other phases of the invention relate to novel methods for automatically controlling and stabilizing such apparatus.

It is, therefore, among the primary objects of this invention to provide a novel construction for vapor condensers and/or radiators wherein air at atmospheric temperature is utilized as the cooling medium; to provide an apparatus of the type described of unusual compactness and extreme capacity; to provide a novel means for controlling or regulating such apparatus which will operate automatically to maintain uniform thermal conditions at the condenser or radiator outlet; to provide a control apparatus which will maintain condenser outlet temperatures sufficiently below the saturation temperature to prevent vapor locking in the feed water pumps and yet sufficiently high for proper cycle efficiency; to provide a more efficient apparatus for driving auxiliary apparatus in aircraft such as electric generators or engine superchargers; to provide an efficient means for waste heat recovery and heating air; and many other objects and advantages as will become more apparent as the description proceeds.

In accordance with the invention, an apparatus is provided which may be adapted with very slight modifications to function either as a condenser for steam or other vapors or as a radiator for liquid cooled internal combustion engines. Furthermore, the invention is suited to assist in aircraft propulsion, or in lift augmentation by providing a novel and efficient means for pumping and adding heat to air for purposes of boundary layer control over an aerodynamic surface. The many disadvantages normally associated with apparatus of this type and which have heretofore restricted the use thereof have been completely eliminated. This fact in conjunction with the many new advantages resulting therefrom will be readily understood and appreciated by those skilled in the art after reading the following detailed description of the drawings forming a part of this specification.

In the drawings:

Figure I is a longitudinal section through a condenser constructed in accordance with my invention and showing also the general arrange-

ment thereof with respect to the cooling fan and the steam turbine.

Figure II is an enlarged sectional view of the fan end of the condenser clearly illustrating the mechanism for varying the pitch of the propeller blades.

Figure III is an enlarged sectional view of the condensate end of the condenser and illustrates in detail the novel control apparatus incorporated therein.

Figure IV is a sectional view taken on the line IV—IV of Figure I to more clearly show the preferred construction of the condenser tubes.

Figure V is a side elevation of an auxiliary steam power unit embodying the condenser of this invention.

Figure VI is a diagrammatic showing of the steam supply control operated by the condenser pressure.

Referring to Figure I, the condenser core 10 is comprised of a plurality of flattened tubes 11 circumferentially disposed with respect to a longitudinal axis A—A, the axes of said tubes 11 extending parallel to said axis A—A, and a plurality of longitudinally spaced, transverse, annular, radiating fins 12 secured to said tubes 11 and circumferentially spacing same, said tubes 11 and fins 12 cooperating to form a substantially circular, central recess 14. Disposed within said recess 14 are a plurality of conoidal diffusers 15, the throats 15' of which are directed toward, and diametrically proportioned with respect to a propeller type fan 16 disposed in the end of said recess 14. By this arrangement each diffuser 15 draws off a definite portion of the air at said recess 14 delivered by the fan 16 and distributes same along the core 10. Another advantage is that it permits the use of a very small fan operating at extremely high speeds and prevents recirculation of the air within the recess 14. The diffusers 15 also serve as turning vanes and direct the air radially outward between the fins 12. It will be noticed that several of the fins 12 between adjacent diffuser cones 15 are provided with curled edges 17 which protrude into the recess 14 and further assist in guiding and directing the air over the condenser tubes 11. The innermost of the conoidal diffusers 15 serves as a guide for the rod 18 which controls the pitch of the fan blades 19, and also as a support for the fan pitch control mechanism as will be hereinafter described.

Further describing the flow of cooling air through the condenser core 10 it is to be understood that the viscosity of air increases with the

temperature. Accordingly the portion of the core 10 nearest the fan 16 tends to have a greater pressure drop between the fins 12 due to the higher temperature. The conoidal diffusers 15 receive the air from the fan 16 and distribute it along the core 10 so that the air which receives the greatest energy from said fan 16 is directed to the portion of the core 10 which has greatest air flow resistance, while the portion of the air emanating from the region nearest the center of the fan 16 is directed to the portion of the core 10 having the least air flow resistance. Accordingly, air is drawn by each diffuser 15 in proportion to the pressure drop to be overcome. This arrangement promotes high fan efficiency and eliminates circulatory flow within the recess 14.

The fan 16 is herein illustrated as being directly driven by a vapor turbine 20 enclosed within a turbine casing 21, the turbine shaft 43 being the coaxial and substantially a continuation of the fan shaft 44. In operation the exhausted working vapor passes from the turbine casing 21 into a diffuser 22 which communicates with an annular collector chamber 23 disposed at the fan end of the core 10. Since the ends 24 of the tubes 11 open into the annular chamber 23, the vapor upon entering said chamber 23 is uniformly distributed to each of said tubes 11. This distribution is further improved by the action of the diffuser 22 in which the residual velocity of the vapor is converted into pressure which forces said vapor through the tubes 11. The vapor in flowing along said tubes 11 is cooled until upon reaching the ends 25 thereof, remote to the fan 16, it is completely condensed. Annular ducts 26 and 27, disposed around the end of the core 10, collect the condensed vapor, hereinafter referred to as condensate, and conduct same to the condenser outlet 28.

In my preferred construction, the inner surface of the condenser tubes 11 is extended by means of transverse strips 29 increasing in number toward the condensate ends thereof as is particularly illustrated in Figure IV. Such construction maintains a more uniform pressure drop within said tubes 11 and increases the preliminary heat transfer. Near the condensate ends of the tubes 11 these transverse strips 29 direct the vapor and condensate in counter flow to the cooling air, as indicated by the dashed arrows 30 (see Figure III), in order to facilitate cooling below the saturation temperature. Referring again to Figure IV, uniform longitudinal spacing of the fins 12 is obtained by providing a plurality of shallow dimples 13.

In the normal anticipated installation, considerable auxiliary apparatus, such as electric generators, superchargers and the like, may be driven by the turbine 20. Due to the variations in the operating power required by such apparatus, the desirability of having a wide range in condenser capacity will be readily appreciated. Accordingly, in the embodiment herein illustrated, I have incorporated a novel method and apparatus for automatically varying the condenser capacity in accordance with the condensing requirements imposed thereon. This control apparatus consists primarily of a fan 16 in which the blades 19 are variable in pitch, and of a mechanism for automatically varying the pitch of said blades 19 in response to the thermal conditions within the condenser 10.

Referring to Figure III the mechanism for varying the pitch of the fan blades 19 is composed of a movable piston 31 disposed within the

cylinder 32 and connected to the spirally grooved shaft 33 by means of the control rod 18. Conduits 31 and 31' extending from said cylinder 32 to a small venturi 38 disposed in the condenser outlet 28 transmit the differential pressure existing between the inlet 39 and throat 40 of the venturi 38 to said cylinder 32. The spring 41 carried by the control rod 18 exerts a force which opposes the forces exerted by the differential pressure above referred to and tends to maintain the fan blades 19 at low pitch. In operation the dynamic flow of the condensate through the venturi 38 produces a differential pressure which acts upon the piston 31 to overcome the force of the spring 41, and thus move the fan blades 19 to a higher pitch. This arrangement provides a continuous stable control of the air flow from the fan 16 in accordance with the thermal conditions of the core 10. Under normal operation the pitch of the fan blades 19 remains relatively flat until vapor appears in the Venturi throat 40 at which time the higher pressures due to said vapor cause the blade pitch to be increased abruptly and the control apparatus becomes very sensitive. Thus the condensate is cooled just below the saturation temperature and the power absorbed by the fan 16 is maintained at a minimum.

The internal construction of the variable pitch blade fan 16 herein illustrated in Figure II is not new in the art and is not deemed essential to this invention. Many such known mechanisms are entirely satisfactory and may be adapted to this use with but slight modification.

The variable pitch hub design shown in Figure II comprises an opposed spirally grooved shaft 33 longitudinally shiftable in a hub 45 forming a gear case driven by the fan shaft 44, on which shaft are mounted driving bevel gears 46 and 47 in spaced facing relationship, both gears meshing with pinions 48 fixed to the inner ends of the fan blades 19. As long as the grooved shaft 33 is not shifted longitudinally, the two gears rotate as a unit with the fan blades, the shaft 33 having a swiveled connection in a bearing 35, longitudinal movement of which, in response to movement of the control rod 18, forcing differential and opposite rotation of the gears 46 and 47, thus turning the fan blades 19 to change their pitch. For example, if the control rod moves to the right in Figure II, as indicated by the arrow 34, the opposite pitch of the two halves of the spirally grooved shaft 33 will rotate the gears 46 and 47 in opposite directions to increase the pitch of the fan blades thus increasing the air delivery of the fan. It will be understood that this differential movement of the gears 46 and 47 is superimposed on the normal rotational movement of the fan shaft 44.

An additional protective device or control apparatus is also incorporated herein comprising a reset type electric (micro) switch 42 which is sensitive to the pressure within the condenser core 10, thus if the condenser pressure would abruptly rise to a relatively high value the switch 42 may be utilized to break the circuit to a solenoid operated valve (not shown) disposed in the steam line leading to the turbine 16, such safety apparatus would prevent damage to the condenser 10 by the high pressure vapor.

Having fully described the invention in its present preferred embodiments, it is to be understood that many modifications and substitutions may be resorted to in a manner limited only by a just interpretation of the following claims.

I claim:

1. In heat exchange apparatus, the combination of a vapor turbine, an air cooled condenser for condensing the exhaust vapor from said turbine, a fan driven by said turbine for supplying air to said condenser, and a control apparatus responsive to the dynamic flow pressure of the exhaust vapor leaving said condenser so as to vary the quantity of cooling air supplied thereto.

2. In heat exchange apparatus, the combination of a vapor turbine, an air cooled vapor condenser, a variable pitch blade fan driven by said turbine and disposed so as to supply cooling air to said condenser, and a control apparatus operating in response to the presence of vapor at the condensate end of said condenser to vary the pitch of said fan blades and thereby increase the quantity of condenser cooling air.

3. In heat exchange apparatus, the combination of air cooled vapor condenser, a variable pitch blade fan for supplying cooling air to said condenser, and a control apparatus for varying the quantity of cooling air supplied to said condenser, said control apparatus comprising a venturi disposed in the condenser outlet and a mechanism operating in response to the differential pressure between the inlet and throat of said venturi to vary the pitch of said fan blades.

4. An apparatus as set forth in claim 3 in which said mechanism comprises a cylinder, a movable piston disposed within said cylinder, conduit means conducting said differential pressure to said cylinder, and a fan pitch operating mechanism between said piston and said variable pitch blade fan.

5. In a power plant, the combination of a steam turbine, an air cooled condenser, means for conducting exhaust steam from said turbine to said condenser, a fan with variable pitch blades for supplying cooling air to said condenser, a control apparatus responsive to the pressure at the condensate end of said condenser to vary the pitch of said fan blades and thereby the quantity of cooling air supplied, and a second control apparatus responsive to excess-

sive pressures within the condenser to shut off the supply of steam thereto.

6. In power plant apparatus, the combination of an air cooled vapor condenser, means for supplying vapor at high temperature to said condenser, a fan with variable pitch blades for cooling said condenser, and a control mechanism for varying the pitch of said fan blades and thereby the quantity of cooling air supplied in response to a change in the thermal conditions at the condensate end of the condenser, said control mechanism comprising a venturi disposed in the condensate outlet, a cylinder, a spring loaded movable piston within said cylinder, conduit means extending from the inlet of said venturi to said cylinder and from the throat of said venturi to said cylinder, said piston being actuated by the differential pressure existing between the inlet and throat of said venturi, and a pitch control mechanism extending between said piston and said variable pitch blade fan.

7. In a steam power plant including an air cooled condenser therefor having a condensate outlet, a variable pitch fan of the propeller type driven by said power plant, said fan being adapted to force air into said condenser, a vapor sensitive mechanism associated with the condensate outlet, and means operatively connecting said vapor sensitive mechanism to the pitch varying mechanism of said fan, said connecting means being adapted to increase the pitch of said fan when said vapor sensitive mechanism is energized by the presence of vapor at said condensate outlet.

8. In combination with a steam power plant of the class described, a variable pitch fan driven thereby, a condenser for the steam adapted to be cooled by the air blast from said fan, and mechanism adapted to be energized by vapor in the condensate from said condenser, said mechanism including a connection to the variable pitch fan whereby to increase the delivery thereof in response to the presence of vapor in said condensate.
